UNITED STATES PATENT OFFICE.

CHARLES HOPPER, OF LOS ANGELES, CALIFORNIA.

MACHINE FOR REPAIRING SCORED ENGINE CYLINDERS.

Application filed March 12, 1921. Serial No. 451,758.

To all whom it may concern:

Be it known that I, CHARLES HOPPER, a citizen of the United States, residing at Los Angeles, in the county of Los Angeles and State of California, have invented new and useful Improvements in a Machine for Repairing Scored Engine Cylinders, of which the following is a specification.

It is the object of this invention to provide a combined milling, planing and grinding machine for operating on the interior of cylindrical or tubular bodies and more particularly for forming channels on the inner walls of engine cylinders and the like, and for grinding and finishing inlays placed in the channels.

Another object of this invention is to provide a machine for facilitating the repair of scored cylinders of internal combustion engines, by means of which the scores may be cut out and dove-tailed channels formed for the reception of a metallic inlay and whereby the channels may be readily formed with oppositely inclined countersunk grooves.

Another object is to provide a construction in a machine of the above character whereby either a milling, planing or grinding action may be performed on the interior of a cylinder as occasion may require, embodying means whereby the milling and grinding action may be effected by mechanical power and the planing by a manual power.

Another object is to provide means for supporting and centering an engine cylinder relative to the mechanism for operating thereon, and to provide various adjustments whereby the machine is adapted to operate on cylinders of various diameters and at various points within the cylinders.

Other objects will appear hereinafter.

The invention is illustrated in the accompanying drawings in which:

Figure 1 is a perspective view of the machine.

Figure 2 is a detail in section and side elevation with portions broken away showing the application of the invention.

Figure 3 is a fragmentary view in end elevation, as seen on the line 3-3 of Figure

2 and illustrating the engine supporting head.

Figure 4 is a detail horizontal section as seen on the line 4-4 of Figure 2. 53

Figure 5 is a view in vertical section and elevation as seen on the line 5-5 of Figure 2.

Figure 6 is a view in vertical section and elevation as seen on line 6-6 of Figure 5. 60

Figure 7 is a detail in plan as seen on the line 7-7 of Figure 6.

Figure 8 is a detail in vertical section showing the detachable grinding head.

Figure 9 is a detail in section and perspective illustrating the manner of centering the engine cylinder by means of a chuck. 65

Figures 10, 11 and 12 are details in perspective showing the manner of planing, milling and grinding the cylinder. 70

Figures 13 and 14 are details in section illustrating the manner of forming the channel.

Figure 15 is a sectional view showing the completed inlay. 75

In general the machine embodies means for adjustably supporting an engine cylinder or the like, a tool operating mechanism adapted to effect either a milling, planing or grinding action on the interior of the cylinder and mounted for vertical, longitudinal, lateral, and radial adjustment relative to the cylinder to dispose a tool in any desired position within the cylinder, and which tool operating mechanism is so designed that a tool may be rotated either axially, diametrically, or obliquely relative to the cylinder, and advanced lengthwise, circumferentially, or radially thereof. 80 85

More specifically 10 indicates a base plate 90 on which is mounted a standard 11 here shown as comprising a vertically disposed plate having a circular opening 12 adjacent to its upper end through which access may be had to the interior of an engine cylinder supported on the standard as will be presently described. 95

Mounted on the back of the standard is a turnable work-holding plate 13 having an opening formed with a marginal flange 14 100 adapted to extend into the opening 12. An annular rib 15 on the plate extends into a

channel on the back of the standard to increase the bearing of the plate.

For securing the work-holding plate against the standard in various positions, 5 a series of bolts 16 are provided and arranged with their heads positioned to engage the shoulders of an annular T-channel 17 formed on the back of the plate as shown in Figure 2; the bolts being each provided 10 with a nut 18 which when screwed on the bolts serve to clamp the plate on the standard. An opening 19 is formed in the plate which, when disposed opposite a bolt receiving opening in the standard, will permit 15 insertion of the bolt.

As a means for securing an engine cylinder on the plate the outer face of the latter is formed with a series of parallel open-ended T-channels 20 adapted to receive the 20 heads of bolts 21 extending through clamps 22 arranged to engage the flanges of an engine cylinder as indicated in dotted lines in Figure 2.

By providing the plate with a series of 25 the channels 20 it is adapted to receive engine cylinders of various sizes which are designed to be supported on the plate with the open end of the cylinder disposed concentrically with the opening in the standard; 30 the engine cylinder being centered by means of a chuck as will be later described.

After the engine cylinder has been secured to the plate the latter may be turned by loosening the nuts 18 to dispose any desired portion 35 of the engine cylinder lowermost.

Mounted on the front face of the standard 11 to have both swinging movement and vertical adjustment thereon is a bracket 23 which forms a support for the operating 40 mechanism of the machine and embodies a leaf 24 secured to the standard by hinges 25 to afford swinging movement and which leaf carries a pair of guide channels 26 in which a slide member 27 is mounted for vertical 45 adjustment.

The slide member carries a bed 28 arranged to project horizontally from the standard when the leaf 24 is closed thereagainst. A clamp latch 29 mounted on the 50 standard is provided to engage the leaf 24 to hold the latter in its closed position.

Mounted on the bed is a longitudinally extending shaft 30 the outer end of which projects beyond the end of the bed and is adapted 55 to receive a removable hand crank (not shown) by which the shaft may be rotated. The inner end of the shaft is fitted with a beveled gear 31 which meshes with a gear 32 on a vertical shaft 33 extending downwardly 60 through a bearing on the slide member 27 and which shaft is formed with a worm 34 and is threaded through a block 35 fixed to the leaf 24; the worm 34 serving as a means to raise and lower the bed on rotation of the 65 shaft 30.

A carriage 37 is slidably mounted on guide flanges 36 on the bed and is adapted to be advanced or retracted relative to the standard, and for this purpose a worm shaft 38 is mounted on and extends lengthwise of 70 and parallel to the shaft 30; the outer end of the worm shaft extending beyond the end of the bed and adapted to be rotated by a hand crank. An internally threaded divided sleeve 39 mounted on the carriage engages the worm shaft 38 and is adapted to be moved in or out of engagement therewith; the members of the sleeve 39 being formed with upwardly projecting lugs 40 which engage slots 41 on a pivoted disk 42 mounted 75 on the upper face of the carriage and provided with a handle 43 by which the disk may be turned to cause the divided members of the sleeve to move toward or away from each other and in and out of engagement with the worm shaft. When the sleeve is in engagement with the shaft, rotation of the latter will cause the carriage to move toward or away from the standard at comparatively slow speed.

Means are provided for manually advancing and retracting the carriage at a speed greater than could easily be effected by the worm shaft which is here shown as comprising a lever 44 pivoted at 45 on the bed and having its short arm connected to the short arm of a bell-crank lever 44' the long arm of which connects with the carriage by a link 46. By moving the threaded split sleeve 80 out of engagement with the threaded shaft and operating the lever 44 the carriage may be freely moved back and forth.

Mounted on the carriage 37 for lateral adjustment thereon is a slide block 47 having a dove-tail channel slidably engaged by a dove-tail flange 48 on the carriage. The dove-tail flange is formed with a longitudinal channel 49 into which a threaded sleeve 50 on the block 47 projects; the threaded sleeve being engaged by a threaded shaft 51 mounted on the carriage and extending lengthwise of the channel 49, the outer end of the shaft 51 projects from the side of the carriage and is adapted to be engaged by a hand crank whereby it may be rotated to advance or retract the block 47 laterally of the bed. A set screw 52 is provided in the block and adapted to engage a shim to securely hold the block against movement or vibration on the carriage.

Formed on the slide block 47 is an open ended cylinder 53 extending in the direction of the length of the bed and which cylinder forms a bearing for a rotary hollow head 54. One end of the head is formed with an end wall 55 and has a flange 56 arranged to abut against the inner end of the cylinder, whilst the opposite end of the head is fitted with a demountable end-plate 57 arranged to abut against the opposite end of the cylin- 120

der. The edge of the end-plate 57 is formed with worm-teeth 58 which are engaged by a worm-pinion 59 mounted on a shaft 60 extending transversely of the bed and supported in bearings carried by the block 47. One end of the shaft 60 projects to one side of the block and is adapted to receive a hand crank by which it may be rotated manually to slowly turn the head and the opposite end of the shaft 60 is connected by a disengageable sleeve 60' to an electric motor 61 carried on the block 47 and which motor is provided for the purpose of rotating the head at comparatively high speed. The ends 55 and 57 of the head are formed with vertically extending slots 62 and 63, and extending through the head and through the slots is a tubular tool carrying shank 64 which is designed to rotate with the head and to be adjustable diametrically of the latter to vary its position relative to the axis of the head. For the purpose of adjusting the tubular shank in the head, a pair of threaded stud shafts 65 are screwed into bosses on the shank and are affixed to worm-wheels 67 carried on the interior of the head, and which worm-wheels mesh with worm-pinions 68 on an adjustment shaft 69 carried by the head. The outer end of the shaft 69 projects forward of the end-plate 57 and is adapted to be rotated by a hand crank to effect movement of the shank radially of the head.

Extending lengthwise of the shank interiorly thereof and supported in ball-bearings therein, is a spindle 70, one end of which is connected through a flexible shaft 71 to a motor 72 by which the spindle may be rotated. The opposite end of the spindle 70 is fitted with a pinion 73 which meshes with a pinion 74 fitted with a hub 75 mounted in a threaded plug 76 screwed in the under side of the shank. The pinion 74 is formed with a tubular end-thrust extension 77 adapted to bear against a threaded plug 78 screwed into the side of the shank opposite the plug 76.

Mounted within the pinion 74 is a tube 79, the lower end of which is formed with a split cone 80 opening in a tapered bore in the hub and adapted to grip the stem of a milling tool; the upper end of the tube being engaged by a threaded connection to a screw 81 extending through the plug 78 and adapted to be turned to advance or retract the tube 79 to cause the tube to be engaged with or disengaged from the milling tool. The outer end of the tubular shaft is fitted with a threaded plug 82 adapted to form a support for a shaper tool and which plug may be removed and replaced by a plug 83, particularly shown in Figure 8, and which plug constitutes a bearing for a shaft 84 carrying a grinding wheel 85 and fitted with a beveled pinion 86 adapted to mesh with the

pinion 74 when the plug 83 is screwed into the end of the tubular shaft.

As a means for determining the normal central positions of the several adjustable parts and by means of which these parts may be reset to various known previous positions, a series of indicating devices are employed. For this purpose the outer face of the guide channel 26 is provided with graduations 87 and the bed 28 is provided with a pointer 88; the pointer indicating a zero graduation when the bed is so disposed that the tubular shaft will be positioned axially of the drum and of the opening 12 in the center. A guide flange 89 on the drum end plate is provided with graduations 90 and a pointer 91 is carried by the tubular shaft and registers with a zero graduation when the tubular shaft is disposed axially of the drum. A pointer 92 on the block 47 co-operates with graduations on the carriage 37 to indicate the relative positions of the block and carriage and to denote when the tubular shaft is positioned on the vertical center of the opening 12. A pointer 93 on the cylinder 53 registers with graduations 94 on the flange 56 to designate the relative positions of the drum and its casing.

In the operation of the invention, the engine cylinder is clamped to the face plate, as before described, and arranged with its axis extending in alignment with the center of the opening 12; the cylinder being centered by means of a chuck 95, as shown in Figure 9. This chuck is fitted with expansion jaws 96 engageable with the margin of the cylinder opening and by which it may be engaged with cylinders of various diameters, and has a cylindrical body 97 which slidably fits the flanged opening in the work supporting plate. The chuck is employed in placing the cylinder in position after which it is removed. When the cylinder is secured to the plate, the latter is then turned to position the scored portion of the engine cylinder lowermost whereupon the face plate is rigidly clamped against the standard by the bolts 16 and nuts 18, as before described.

The bed is then adjusted vertically by rotating the shaft 30 to position the center of the drum approximately opposite the center of the engine cylinder; the leaf 24 being disposed in its closed position.

If it is desired to effect a planing action on the engine cylinder, a suitable cutting tool 98 is mounted on the end of the shaft 64 to project downwardly therefrom, as shown in Figure 10. The carriage 37 is then disengaged from the shaft 38 and the lever 44 operated to advance the carriage 37. The cutting tool is then lowered into contact with the engine cylinder by rotating the shaft 69, whereupon the cutting action may

be effected by longitudinal movement of the carriage by manually operating the lever 44, or the carriage may be advanced slowly by re-engaging the sleeve 39 with the shaft 5 38 and rotating the latter. If desired, the carriage may be advanced by the screw shaft 38 and retracted more speedily by operation of the hand lever.

When it is desired to mill a dove-tail 10 channel in the cylinder, the planer tool is removed and a straight milling tool affixed to the stock in the pinion 75 and driven from the motor 72.

In the milling operation the tool may be 15 advanced longitudinally of the cylinder, either by rotation of the threaded shaft 38 or the hand lever 34. Lateral movement of the milling tool is effected by manually rotating the drum by turning the shaft 60 20 previously disconnected from the motor 61.

In milling the channel, the milling tool is advanced longitudinally of the cylinder in a vertical position and in alignment with the vertical center of the cylinder, as indicated in Figure 13, so as to form the channel with vertical side walls; a side cutting milling tool being employed. The initial cut will thus be formed to extend along the vertical center of the cylinder. On completing the length of the cut, the milling tool is advanced to either side of the channel previously formed where it is desired to form the channel of a width greater than the diameter of the milling tool. This 30 lateral movement of the milling tool is effected by shifting the block 47 and the head thereon, during which movement the milling tool will remain in a vertical position. The milling tool is then again advanced lengthwise of the cylinder to widen 35 the channel.

On completing the initial cut of the channel whereby it is formed with side walls paralleling a radius of the cylinder, 45 the milling tool is disposed at an angle and lowered to increase the depth of its cut, so as to form the channel with an inclined side wall terminating in a groove at the juncture of a bottom and side wall of the 50 channel, as shown in Figure 14. The positioning of the milling tool at an inclination is effected by turning the head through the medium of the shaft 60, and lowering of the milling tool is effected by operating the 55 adjustment shaft 69. The milling tool is obviously inclined in one direction when undercutting one side wall of the channel, and is inclined in the opposite direction when undercutting the other side thereof. 60 The completed channel will thus be formed with oppositely inclined side walls which are preferably formed at an inclination of about 10 degrees from the vertical, and the channel will have spaced grooves 65 in its bottom wall whereby an inlay 99,

placed in the channel as shown in Figure 15, will be formed of increased thickness along its edges, thus reinforcing the inlay, and securely anchoring it against displacement.

In forming the channel in the manner before described, the use of an undercutting milling tool is obviated as the channel may be formed by a straight side cutting tool.

Before placing the inlay in the channel, 75 the bed is swung to one side to give access to the interior of the cylinder, the hinged mounting of the leaf 24 permitting ready movement of the mechanism to one side. The inlay may be put in place in any desired manner, whereupon the head is swung back into position, and a grinding tool, such as shown in Figure 8, is then attached to the end of the shaft 54, with the pinions 80 86 and 74 intermeshing. The head is then positioned in axial alignment with the engine cylinder, and the shank is adjusted on the head to dispose the grinding wheel in position to grind the inlay flush with the inner surface of the engine cylinder. The head may then be oscillated by means of the shaft 60 to grind the inlay flush with the cylinder. When it is desired to grind the interior of the cylinder throughout, the shaft 60 may be connected to the motor 61 85 and the head rotated so that the grinding wheel will traverse the inner wall of the engine cylinder circumferentially thereof; the grinding wheel being rotated on the tubular stem by the motor 72 during this operation, and the grinding wheel advanced lengthwise of the cylinder at the same time by advancing the carriage, as before described.

By mounting the cylinder on the turnable plate opposite to and concentric with the openings in the plate and standard, the cylinder may be turned to dispose a score 100 therein in any desired position relative to the tool, and by providing the various gage marks the position of the tool relative to the center of the cylinder may be readily adjusted, as occasion may require; each of the gage marks being provided with a zero mark, to which a pointer would indicate 105 when the adjustable part would be in such position as to dispose the center of the head and shank in alignment with the center of the cylinder when the several adjustable parts are all in the zero position. This enables rapid adjustment of the parts 110 to suit cylinders of various diameters.

In event it is desired to operate on the cylinders of an internal combustion engine without removing the engine from its mounting, the same may be effected by detaching the bed from the standard, and supporting it in any desired manner to position the tubular shaft vertically and in operative relation to the cylinder.

Whilst the invention has been specifically described, it is manifest that various changes may be made in the details of construction and the arrangement of parts without departing from the spirit and scope of the invention as set forth in the appended claims, and I, therefore, do not limit myself to the precise construction shown.

What I do claim as my invention, and 10 desire to secure by Letters Patent, is—

1. In a machine of the character described, a rotary head, a shank projecting through said head and adapted to extend axially thereof, means for adjusting said 15 shaft laterally in said head parallel to the axis thereof, screw means for adjusting said head vertically, screw means for adjusting said head laterally, and means for reciprocating said head longitudinally.

2. In a machine of the character described, means for adjustably supporting a cylinder, a vertically adjustable bed-frame, a carriage slideable longitudinally of said bed-frame, a rotary head on said carriage 25 adjustable transversely thereof, a tool-supporting shank extending longitudinally through said head and adjustable diametrically therein parallel to the axis thereof.

3. In a machine of the character described, means for adjustably supporting a cylinder, a hinged and vertically adjustable bed-frame, a carriage slideable thereon, a block slideable transversely of the carriage, a rotary head on said block, a shank extending longitudinally of said head and adapted to extend axially thereof, and the 35 means on said head for adjusting said shank diametrically of said head and maintaining it parallel with the axis of the latter.

4. In a machine of the character described, a bed-frame, a carriage slideable

thereon, a screw means for advancing said carriage, means for disengaging said screw means, a lever operated means for advancing said carriage on release of said screw 45 means and tool supporting and operating mechanism supported on said carriage.

5. In a machine of the character described, a standard, a work supporting plate on said standard having an opening therein, means for supporting an engine cylinder on said plate with its open end disposed concentric with the opening in the plates, means whereby said plate may be rotated around an axis extending centrally through 55 said opening, and means for clamping said plate to said standard.

6. In a machine of the character described, a standard, a work supporting plate therein having an opening therein, means 60 for attaching an engine cylinder on said plate with its open end extending axially of said opening, a bed-frame adjustable vertically on said standard beneath said opening, a rotary head mounted for lateral and longitudinal movement on said bed-frame, and a tool-supporting shank extending longitudinally through said head parallel with said bed-frame adapted to be adjusted diametrically of said rotary head.

7. In a machine of the character described, a bed-frame, a carriage slideable longitudinally thereof, a rotary head on said carriage adjustable transversely thereof, a tool-supporting shank extending longitudinally of said head, and slideable diametrically thereof, means for adjusting said shank to dispose it at various positions diametrically to the head and parallel to the axis thereof, a spindle carried by said 75 shank, and means for rotating said spindle.

CHARLES HOPPER.
